VENEER EDGE GLUING MACHINE

Oscar S. Bolling, Minneapolis, Minn., assignor to
Mereen-Johnson Machine Company, Minneapolis, Minn., a corporation of Minnesota

Application February 8, 1943, Serial No. 475,104

12 Claims. (Cl. 144—279)

My present invention provides an improved and highly efficient machine for assembling and gluing together the edges of wooden veneer sheets or strips and, generally stated, the invention consists of the novel devices and combinations of devices hereinafter described and defined in the claims.

As is well known, the wooden veneer sheets or strips are thin and have very narrow edges which must be brought together very accurately, immediately after glue has been applied to the edges thereof, and must be firmly held together while the glue is being dried or set. In this improved machine the operation just noted is performed by upper and lower feed chains or link belts of novel construction. As their major features these chain or belt links are provided with gripper or vise-acting supplemental links or sections attached to the main links for lateral sliding movements. The chains, with their supplemental links, are caused to travel through very gradually contracted longitudinal channels or runways.

Glue applying means operate to apply glue to the edges of the veneers just prior to bringing the edges of the veneers together and by means of electrical heating strips or elements the applied glue is dried or set while the edges of the veneers are firmly held together, during their travelling movement through the machine.

The laterally movable supplemental links or chain sections are arranged to run between lower skids or chain-supporting surfaces and overlying yieldingly downwardly pressed shoes which cause the co-operating upper and lower right and left supplemental links to grip the veneers with a vise-like action and then, under the action of the converging runway, to bring the glue-coated edges of the veneers into tight contact and hold the glue-coated edges of the strips firmly together while it is set and hardened.

The improved machine also includes an initial or primary veneer feeding means operative on the veneers while the glue is being applied to the edges thereof and while the veneers are being presented to the feed chains or belts.

This so-called initial feeding and glue-applying mechanism is designed and operates in important relation in respect to the main feed chains or belts but is capable of use as an initial feeding means in machines employing other than the said novel feed chains or belts. On the other hand, the initial feeding and gluing mechanism used in connection with the highly important and improved feed chains or belts may vary materially

from that herein disclosed and made a part of this application.

The above and other important features will be hereinafter more fully disclosed and described in connection with the drawings hereunto appended and forming a part hereof.

A commercial form of the improved machine is illustrated in the accompanying drawings wherein like characters indicate like parts throughout the several views.

Referring to the drawings:

Fig. 1 is a view in perspective looking chiefly at the machine toward the receiving end thereof;

Fig. 2 is a view in perspective looking at the machine chiefly toward the delivery end thereof;

Fig. 3 is a view partly in side elevation and partly in longitudinal vertical section, some parts being broken away, and in which the left hand or delivery portion of the machine has certain parts sectioned on the line $x-x$ of Fig. 4, and the right hand or receiving portion of the machine, as shown in Fig. 3, has certain parts sectioned on the line $y-y$ of Fig. 4;

Fig. 4 is a transverse vertical section, some parts being broken away, taken on the line $4-4$ of Fig. 3;

Fig. 5 is a transverse vertical section taken in section on the line $5-5$ of Fig. 3;

Fig. 6 is a transverse vertical section taken on the line $6-6$ of Fig. 3;

Fig. 7 is a plan view, with parts broken away, showing the receiving table and immediately connected portions of the machine, structures above the table being removed or omitted;

Fig. 8 is a fragmentary view in side elevation, with some parts sectioned, showing the receiving end of the feed table and the glue applying mechanism;

Fig. 9 is a plan view showing one of the chain-conveying sprockets for the feed chains;

Fig. 10 is a section taken on the line $10-10$ of Fig. 9;

Fig. 11 is a plan view showing a portion of one of the feed chains or belts showing, for example, portions lying just below the line marked $11-11$ on Fig. 3; and

Fig. 12 is a section taken on the line $12-12$ of Fig. 11.

As best shown in Figs. 1 and 2, all of the parts of the machine are mounted on a supporting base, preferably in the form of a cast metal box-like structure 15 the top of which supports a horizontal feed table shown as made up of a primary or main section 16 and extended leaves $16a$. The main table 16 , see particularly Figs. 4 and 7, is

formed with a channel in which cam-acting chain-contracting rails 17 are seated. Here it may be stated that these rails or surfaces 17 extend longitudinally of and through the major portion of the feed table and converge in a direction from front to the rear of the table only about one-fourth of an inch in eight feet, more or less, the importance of which will be hereinafter noted.

The feed table illustrated is very wide and projects far beyond the main table section 16. To support mechanism above the channel or chain runway of the table section 16 the upper portion of the base 15, at one side of the table, has a heavy steel arm 18 that is cast integral with the base or otherwise rigidly secured thereto, and overlies and is spaced from the feed table, and at its end is formed with heavy integrally formed or rigidly secured sleeves 19, see particularly Figs. 1, 2, 3 and 4.

In this improved machine link belts or feed chains of novel construction are provided. These link belts, both upper and lower, are of similar novel construction, each involving main or primary links 20 and supplemental or secondary links 21, see particularly Figs. 3, 11 and 12. The links 20 and 21 are pivotally connected by long transverse hinge pins 22. These hinge pins 22 connect together the links 20, connect together the links 21, and permit lateral shifting movements of the links 21 in respect to the main links 20. During their operative feeding runs through the machine, the feed chain links 20 and 21 pass through converging channels formed by the converging surfaces of the rails 17. When the feed chain links start their operative feed runs through the machine, the secondary links 21 are spaced laterally from their respective cooperating primary links, but as they progress through the machine the secondary links are progressively forced to move laterally toward their respective main links 20 and, as will hereinafter be made clear, it is this lateral movement of the secondary links 21 with respect to the primary links 20 that is responsible for maintaining parallel veneer strips in tight edge-gluing relation one to the other during their movements through the machine. The main links 20, see particularly Fig. 12, are provided with V-shaped notches or depressions 23 that adapt them to run on properly constructed sprocket wheels, such as shown in detail in Figs. 9 and 10, wherein the sprocket wheels 24 are shown as provided with V-shaped teeth 25 and with laterally spaced knife-edged or wedge-acting flanges 26. Here it may be further stated that the teeth 25 are arranged to run in the notches 23 of the main links 20, while the wedge-acting flanges 26 are adapted to project between the main links 20 and shiftable or secondary links 21 to cause the hereinafter more fully noted spreading action of the feed belts or chains. The flange 26 is shown as notched at 27 to clear the hinge points of the links.

Supported above the feed table and extending longitudinally of the chain or belt-guiding channel thereof, is a hanger frame or hood 28 that is rigidly secured to the lower ends of a pair of suspending posts 29, see Figs. 3 and 4, that extend vertically through and are vertically adjustable in the head forming sleeves 19 of the rigid arm 18. The upper portions of these posts 29 are externally threaded and extend upward through the top plates 30 and internal flanges 31 of said sleeves. Working as a nut on the threaded ends of the posts 29 are post adjusting elements shown as in the form of worm gears 32. These worm gears are held against endwise or vertical move-

ments by the heads 30 and flanges 31. As shown, the posts 29 are hollow and extended therethrough are nut-equipped rods 33, the lower ends of which are shown as screwed into seats in the hood 28.

5 The nut-acting worm gears 32 are in mesh with worms 34 of a shaft 35, which latter is journaled in the head forming sleeves 19 and, as best shown in Fig. 3, is provided at its extended end with an operating wheel or handle 36. By manipulation of the shaft 35 the two nut-acting gears 32 may be simultaneously operated to raise both ends of the hood or to simultaneously lower the same. Rigidly secured to the hanger frame hood 28 and located below the same is an upper chain-carrying frame, shown as made up of laterally-spaced lower plates 37, an upper plate 38, and longitudinally spaced struts or members 39. Housing plates 37a are shown as applied to plates 37 and 38. All of said elements 28, 37, 38, and 37a are tied together for common vertical adjustments.

In Fig. 3 only the lower feed chain or link belt made up of the above noted elements 20 and 21 is indicated as an entirety by the character A, 25 and the upper feed chain or link belt made up of the said elements is indicated as an entirety by the character B.

In Fig. 3 the veneer receiving end of the machine is at the right hand and at this end of the 30 machine the chains A and B are arranged to run over sprockets 24 of the detailed structure illustrated in Figs. 10 and 11. At the delivery end of this machine, which is at the left in respect to Fig. 3, the chains A and B run over sprockets 24 such as noted, except that at this delivery end of the machine the knife edged flanges 26 may be omitted.

The lower right hand sprocket 24, see Figs. 3, 40 4, 6 and 7, is journaled on a stud or spindle 40 that is fixed in a block 41, rigidly secured to the bottom of the feed table 16. Preferably ball bearings 42 hold the said sprocket against lateral displacement on said stud. This lower right hand sprocket, as will presently be noted, is driven 45 by the lower chain, but serves to transmit motion to a glue-applying wheel presently to be described; and hence, said sprocket is provided with an axially projecting shaft 43 that carries a sprocket wheel 44.

50 The upper right hand sprocket 24, see particularly Figs. 3 and 6, is journaled on a spindle 45, the ends of which are rigidly secured to the depending arms 46 of a bell crank lever 47, the upper arm of which is subject to an adjustable coiled spring 48 of a tension device which, as shown, includes a nut-equipped stud 49. The arm 47 of the bell crank lever works freely on the stud 49 and the depending arms thereof work freely through a clearance passage 50, as best shown in Fig. 3. Bell crank 47 is pivotally connected to frame or hood 28 by hinge bolt 47a.

The two sprockets 24 at the left, as shown in Fig. 3, drive the opposing portions of the feed belts or chains A and B in a direction from right toward the left, and hence, keep the co-operating adjacent portions of the two chains under tension to produce the proper feeding action, and without buckling of the chains. Otherwise stated, the upper and lower left hand sprockets are rotated in reverse directions, to wit: in the direction of the arrows marked thereon on Fig. 3. It may be here also noted that the lower chain A is caused to run on the bottom of the groove in the feed table, between the

converging rails or surfaces 17. At points over the lower sprockets chain A passes freely through openings, as best shown in Fig. 3.

As just above noted, the upper and lower left hand sprockets 24 are chain-driving members. The lower left hand sprocket 24 is mounted on a shaft 51 that is journaled in a fixed bearing of the feed table and is connected to or formed as an extension of a quite long shaft 52. The upper left hand sprocket 24 is secured to and carried by a shaft 53, see Fig. 3, which, by a knuckle joint 54 or otherwise, is connected to a long shaft 55, see particularly Fig. 2. The extended end of the shafts 52 and 55 are shown as journaled in a bracket 56 secured to the base of the arm 18, as clearly shown in the said Fig. 2. The bracket 56 is shown as formed with a gear housing 57. Shaft 55 is provided with a spur gear 58 that meshes with a similar gear 59 on shaft 52. Both gears 58 and 59 are shown as located within a housing 57.

So far as the driving mechanism of the present machine is concerned, the shaft 52 may be treated as a major power-transmitting element that receives power from any suitable source, such, for example, as from an electric motor 61 mounted in the base 15 and connected to shaft 52 by a well-known or any suitable speed-reducing transmission mechanism.

Set into the bottom of the lower plate 31 of the rectangular chain carrier frame are gathering rails or surfaces 17a that directly overlie the gathering rails 17 and, like the latter, converge slightly from the receiving toward the delivery end of the machine. Otherwise stated, the rails 17a are parallel with the underlying rails 17 in a direction from right toward the left in respect to Fig. 7. By reference particularly to Fig. 4, it will be noted that the shiftable supplemental links 21 of the upper feed chain or belt, at their outer edges, are subject to the adjacent faces of the rails 17a while the corresponding links of the lower chain are subject to the gathering action of the rails 17.

The supplemental or vise-acting links or chain sections 21 are arranged to run under and to be pressed downward by pressure shoes 62. These shoes are spaced along the chain channel and are pivoted or otherwise secured to the lower ends of vertically movable pressure plungers 63, see particularly Figs. 4 and 6. These plungers work through seats in the upper plate 38 and in the inturned flanges of the lower plates 37. Working with threaded engagement on the plungers 63 are nuts 64 and slideable washers 65 and between the nuts and washers are coiled tension springs 66. In Fig. 4 there is shown a cross bar 67 that is not in any way attached to the adjacent plungers 63 and the function of which will hereinafter be noted. This statement is made at this time to avoid confusion.

Mounted in the struts are block-like portions of the upper chain carrier frame, one at each side of the chain runways, is a pair of parallel rock-shafts 68, best shown in Figs. 3 and 4. These rock-shafts are provided with short inwardly projecting tappet arms 69 that bear one on each of the washers or slide collars 65 of the respective plungers 63.

Each rock-shaft 68 has an outwardly and upwardly projected major arm 70 that extends to points above the crown plate 28 and are there provided with pivotally connected nut blocks 71. The nut blocks 71 of the arms 70 are engaged by the reversely threaded ends of a transverse screw-

rod or shaft 72 that is journaled in a bearing 13, the latter being rigidly secured on the vertically adjustable crown plate 28. The screw-threaded shaft 72 is provided with a bevel gear 74 that meshes with a bevel gear 75, see Figs. 3 and 4, of a shaft 76, which latter is journaled in suitable bearings 77 and 78 on the hood 28 and is provided with a conveniently located operating handle or wheel 79. The screw-shaft 72 by the hub of its bevel gear 74 and a collar 80 is held against endwise movements. At this point it is only desirable to state that by rotation of the shaft 76 the rock-shafts 68 and their tappet arms 69 may be oscillated to vary the tension of the springs 66, and hence, the pressure of the shoes 62 on the link sections 21.

Located immediately below the upper run of the lower chain is a longitudinally extended electrical heating coil or element 81 contained in a heat radiating casing 82 located in a depressed channel of the feed table 16, see particularly Fig. 4. This lower heating element is approximately the width of the main elements 20 of the lower chain and the said chain runs in contact with the upper surface thereof. By means of nut-equipped studs 83 this heating element 81 may be adjusted and kept level.

Located between the inner flanges of the plates 37 and running in contact with the lower run of the upper chain, also see Fig. 4, is an upper electrical heating element 84 contained in a heat radiating casing 85. This upper heating element is attached to and supported by a plurality of the heretofore noted cross bars 67. Engagement of the ends of the cross bars 67 with the top flange of the plates 37 limits the downward movement of the upper heating element which supports the latter so that it will rise and fall slightly and always rest on the main links 20 of the lower run of the upper feed chain or belt.

Both the lower and the upper heating elements just described extend longitudinally of the machine nearly or quite the full extent of the parallel co-operating portions of the upper and lower chains; but in Fig. 3, the section there illustrated shows the said heating elements only in the right hand portion of said figure.

In Figs. 5 and 6 the thin veneer strips that are to be assembled and glued together by this machine are marked with the character Z. In co-operation with the machine so far described, I provide an improved form of glue applying mechanism best shown in Figs. 3, 5, 7 and 8. To form suitable supports for the parts of this glue applying mechanism now to be described, the crown plate 28 is forwardly extended beyond the receiving portions of the feed chains and the feed table 16 is provided with a rigidly secured table extension or supplemental section 16a.

As best shown in Figs. 5, 7 and 8, the numeral 86 indicates a glue applying wheel carried by a transverse shaft 87 journaled in bearings 88 secured on the bottom of the table extension 16a. This shaft 87, at one end, has a sprocket 89 over which and the heretofore noted sprocket 44 of shaft 43 runs a sprocket chain 90, see particularly Figs. 7 and 8. Wheel 86 has a very thin or narrow glue applying blade 91 that is in a vertical plane aligned with the medial longitudinal plane of the feed belts or chains and projects through an opening 92 formed in the table extension 16a. Secured on the feed table and extending to the receiving portions of the two feed chains is a very thin or narrow aligning flange or blade 93 that is aligned with the blade 91 of the wheel

86 but is segregated or cut away to clear the said wheel and its flange.

The flange or blade of wheel 86 is arranged to run in the liquid glue of a glue pot 94. This glue pot is shown as adjustably supported by a screw 95 mounted in a supporting post 96 secured to and depending from the feed table 16. Glue pot 94 is shown as provided with a coldwater compartment 97 for keeping the glue in fluid condition. The glue preferably used in this machine is of a character that sets very rapidly under the action of heat and should be kept in cool condition while being applied to the edges of the veneer strips, and should not set until the edges of the veneer strips have been pressed together and subjected to the heating elements 81 and 84.

As a primary feed device the glue wheel carrying shaft 87 is provided with spaced and externally serrated feed wheels 98 that project upwardly slightly through openings in the table extension 16a. The location of the glue pot is such that it has been necessary to provide the pot 94 with a dry chamber 99 within which the right hand feed wheel 98 may run.

Located over the feed wheels 98 are primary pressure rollers 100 shown as journaled to vertically movable plungers 101 which latter are vertically adjustable in a front end extension of the hood forming member 28.

Loosely rested on the top of the front end extension of the hanger frame or hood 28, see particularly Fig. 5, is an angle plate 102 which has upturned ears 103 in which a crank shaft 104 is journaled. This crank shaft, at one end, has a handle 105 and on its end portion adjacent to the ears of plate 102 said crank shaft has rigidly secured thereto lift lugs 106, see also Fig. 3 wherein crank shaft handle 105 and its lift lugs 106 are turned into inoperative positions.

The plungers 101, at their upper ends are formed with threaded trunnions equipped with nuts 107. Plungers 101, at their intermediate portions, are provided with inwardly projecting arms 108. Overlying the inner ends of the arms 108 is a floating coupling block 109 which has depending trunnions 110 that work through slots or slightly enlarged holes in the free ends of the arms 108.

As best shown in Fig. 5 the numeral 111 is a tension screw that works with threaded engagement through the front end extension of frame 28 and works freely through an opening in the plate 102. This screw presses downward on the tension spring 112 and presses the latter against a pressure bar 113 that rests on top of the arms 108 of the plungers 101 and through the latter presses the upper rollers 100 onto the veneer strips Z.

The numeral 114, see Figs. 3 and 5, indicates an adjusting screw that is swiveled in a flange of the front end extension of frame 28 and has threaded engagement with the coupling block 109. Numeral 115 in the views just noted is a stud or pin rigidly secured to the depending flange of frame 28 with its extended end working in a notch 116 formed in said block 109. Stud 115 simply guides the block for forward and rearward sliding movements free for vertical movements but against rotary movements.

The downward tension that will be exerted on the rollers 100 may, as above indicated, be varied by adjustments of the tension screw 111. By adjustments of the screw 114 the plungers 101 may be oscillated, and rollers 100 may be set on

angles slightly converging forwardly or in the direction of the feed of the veneer strips; and when the rollers are thus set, they will tend to force the veneer strips against the aligning flange 93, and, hence, properly align for the application of the glue thereto from the flange 91 of the glue wheel 86. Here it may be stated that the lower feed rollers 98 are set parallel or preferably provided with transversely grooved peripheries which while they have strong frictional feeding action will not greatly resist the slightly shifting actions produced by the converging upper rollers.

Again referring to Figs. 1 and 3 it will be noted that overlying the glue pot and glue applying roller is an initial guide shoe 117 that is slotted or bifurcated to clear the flange 91 of the glue applying wheel. This shoe 117, by means of overlapping lugs and a coupling bolt 118, is hung from the lower end of a rod or plunger 119 that works slidably through a sleeve 120 that is rigidly secured to and depends from the front end extension of hanger frame 28. The upper end of sleeve 120 is flanged and rigidly secured to the frame 28, as best shown in Fig. 3. The upper end of plunger 119 is reduced and threaded and provided with a nut 121 by the adjustment of which later plunger 119 and shoe 117 may be vertically adjusted. Said shoe 117 is shown as provided on its under side with obliquely depending thin spring blades 122 that directly engage the veneer strips and press downward thereon with a predetermined pressure that is variably controlled by vertical adjustment of the plunger 119 and shoe 117.

In Fig. 3 at the left hand end or delivery end of the machine the numeral 123 indicates chain wipers which, however, constitute no essential part of the invention. In Fig. 2 the group of elements 124 may be assumed to be parts of transmission mechanism which, however, constitute no essential part of the present invention and need not, for the purpose of this case, be considered.

Summary of operation

The operation of the machine above described in detail may be summarized as follows.

The veneer strips Z are placed on the receiving end 16a of the feed table 16 with their adjacent edges pressed against the aligning flange 93 and are manually delivered to the initial feed rollers 98 and 100 and by the latter will be fed forward with the adjacent edges of the veneers pressed against the blade 91 of the glue-applying roller 86. When the upper rollers 100 are set slightly converging in a forward direction, they will keep the edges of the veneer strips pressed against the blade 91 and against the aligning flange 93. When the veneer strips pass the delivery end of the aligning flange 93, see particularly Fig. 7, the veneer strips, with the glue applied to the edges thereof, will be delivered to the upper and lower main feeding mechanism, to wit, between the upper and lower feed chains or belts A and B, and thereafter the feeding movement of the veneer strips will be controlled by said chains.

Under initial engagement of the feed chains or belts, the veneer strips will be clamped with a vise-like action between the supplemental link sections 21 of the upper and lower feed belts. As the links of the belts move through their respective slightly converging guide channels or runways, the supplemental links 21 will be grad-

ually forced closer together, thereby forcing the interposed veneer strips together and insuring good pressure contact between the glue applied edges of the veneer strips during their passage through the machine.

During substantially the entire travel of the veneer strips through the machine, their glue applied edges will be subject to the upper and lower heating elements 81-84 and, hence, the glue will be completely set and the veneer strips permanently glued together during their travel through the machine.

During the travel of the veneer strips through the machine, the right and left hand supplemental links 21 of the upper chain will be downwardly pressed by the yielding shoes 62 so that the gripping action between lower and upper supplemental links 21 will be maintained. The tension thus produced on the supplemental links 21 may be varied by the heretofore described action of the rock shaft 68 and the connections thereto. In practice the tension between the upper and lower supplemental sections of the two link belts or chains would advisably be such that proper pressure between the glued applied edges of the veneer strips will be maintained with little slippage of the supplemental links on the veneer strips gripped between the same.

The lower feed belt or chain does not require any slack adjustor but the upper belt should be kept free from slack and this is accomplished through means already described, to wit, the bell crank lever 46 and spring connection 48-49.

I have now described the various features of my invention as incorporated in a commercial machine, but it will be understood that various alterations and changes therein may be made within the scope of the invention herein disclosed and sought to be claimed.

The feed chains or link belts with supplemental link sections attached to the main links with freedom for lateral shifting movements are thought to be broadly new and especially as combined with means for gradually forcing the laterally spaced supplemental links closer and closer together progressively in the direction of the travel of the chains. It is highly important and the best known means for effecting this gradual chain contracting movement of the supplemental links is thought to be the gradually converging chain guideways. It is also important that these link belts or chains with their supplemental links or sections should be power driven at the same traveling speed. Chain guideways and chain supports must be arranged to guide the cooperating portions of the upper and lower feed belts along cooperating courses and in such relation that the left hand supplemental links of upper and lower chains will move in veneer-gripping action and the right hand supplemental links of the upper and lower chains will move in cooperative veneer-gripping action.

As the link belts or chains pass around the right hand sprocket wheels 24, the wedge-acting blades 26 enter between the main and supplemental link sections and spread the chains, so that the upper and lower supplemental link sections 21 are brought into initial engagement with the veneer strips and into clamping and gripping action thereon, while the chains are thus spread. However, these chains are, as already indicated, very slightly laterally spread and, hence, will freely enter the contracting guide channels. The contacting and overlapping portions of the link members 20 and 21 may be slightly bevelled, if

found desirable, to make more certain the proper engagement of the blades to produce the above spreading action.

In Figs. 3 and 5, the lever 105 is shown as raised so that the initial feed rollers 100 will be yieldingly pressed down by spring 112. However, when lever 105 is pressed down, lift lugs 106 will raise the feed rollers 100 out of co-operative relation in respect to the lower initial feed rollers 98.

Attention is again called to the fact that the rock-shafts 68 are mounted on the upper frame structure and, hence, are vertically adjustable therewith; that by oscillation of said shafts and their arms 69, the tension of the shoe-pressing springs 66 may be varied; and that such adjustments for tension of the said shoe-pressing springs is not changed by vertical adjustments of the upper frame to adapt the machine to be set for different thicknesses.

As already described, the upper frame or hood 28 is made vertically adjustable by rotation of shaft 35, and when this frame 28 is raised or lowered, all the parts carried thereby, including the upper link belt or feed chain and the yieldingly pressed shoes 62, will be also vertically adjusted. Such adjustments adapt the machine to be set for proper operation upon veneer that varies considerably in thickness.

In accordance with the statute, I have now described a commercial machine embodying what I, at present, believe the preferred embodiment of my present invention, but it will be understood that various alterations and changes therein may be made within the scope of the invention herein disclosed.

What I claim is:

1. A feed mechanism of the kind described, including a feed belt made up of pivotally connected main links and supplemental links, the latter being arranged one on each side of each main link and mounted for lateral sliding movements in respect thereto, in combination with means for laterally contracting said link belt by progressively forcing the supplemental sections closer and closer to the main links during the feeding movement thereof, and means for laterally spreading the supplemental links with respect to the main links during inoperative movements of the chains.

2. The structure defined in claim 1 in which the main links are pivotally connected by pins that project laterally therefrom at both ends and on the projecting ends of which pins said supplemental link sections are pivotally and slidably mounted.

3. A feed mechanism of the kind described, including a feed belt made up of pivotally connected main links and supplemental links, the latter being arranged one on each side of each main link and mounted for lateral sliding movements in respect thereto, in combination with a gradually contracting guideway through which the composite link belt is moved during the feeding action, and means for laterally spreading the supplemental links with respect to the main links during inoperative movements of the chains.

4. A feed mechanism of the kind described, in which there is an upper and a lower link belt such as defined in claim 1, said feed belts being arranged so that the main links of said belts are aligned for cooperation, the left hand supplemental link sections of said upper and lower belts are aligned for cooperation and the right hand supplemental link sections of said upper and lower belts are aligned for cooperation.

5. In a machine of the kind described, a feed table having a gradually contracted link belt guideway, and an overlying belt-supporting frame and also having a gradually contracted belt runway, of cooperating lower and upper link belts each made up of main links and laterally shiftable supplemental gripper-acting links, movable through the respective guideways of said feed table and supporting frame, belt driving and guiding wheels for said feed belts mounted respectively on said table and overlying frame, power-driven connections to certain of said wheels for driving said belts through their respective guideways, means laterally shifting the supplemental links outwardly during their inoperative movements, said gradually contracted guideways serving to gradually shift the supplemental links laterally inwardly with respect to their main links during their operative feeding movements.

6. In a machine of the kind described, a feed table having a gradually contracted link belt guideway, and an overlying belt-supporting frame and also having a gradually contracted belt guideway, of cooperating lower and upper link belts each made up of main links and laterally shiftable supplemental gripper-acting links on opposite sides of the main links, movable through the respective guideways of said feed table and supporting frame, belt driving and guiding wheels for said feed belts mounted respectively on said table and overlying frame, power-driven connections to certain of said wheels for driving said belts through their respective guideways, means for vertically adjusting said upper frame and the parts carried thereby means laterally shifting the supplemental links outwardly during their inoperative movements, said gradually contracted guideways serving to gradually shift the supplemental links laterally inwardly with respect to their main links during their operative feeding movements.

7. A feed mechanism of the kind described, including a belt made up of pivotally connected main links and supplemental links, said supplemental links being attached to the main links for limited lateral movements, and power-driven sprockets over which said feed belt is mounted to run, certain of said sprockets having wedge-like flanges operative between the main and supplemental links of said feed belt to spread the same, and means for laterally contracting the link belt by progressively forcing the supplemental links closer and closer to the main links during their feeding movements through the machine.

8. A feed mechanism of the kind described, including a belt made up of pivotally connected main links and supplemental links, said supplemental links being attached to the main links for limited lateral movements, and power-driven sprockets over which said feed belt is mounted to run, certain of said sprockets having wedge-like flanges operative between the main and supplemental links of said feed belt to spread the same, and a converging guideway through which the links of said belt are arranged to move and by which latter said belt is progressively contracted transversely.

9. A feed mechanism of the kind described in which there is an upper and a lower link belt such as defined in claim 1, said feed belts being arranged so that the main links of said belts are aligned for cooperation, the left hand supplemental link sections of said upper and lower belts are aligned for cooperation and the right hand supplemental link sections of said upper and lower belts are aligned for cooperation, and guiding and driving sprockets for said link belt having projecting wedge-shaped flanges operative between the main and supplemental links of said belt to spread the same and means for laterally contracting the link belt by progressively forcing the supplemental links closer and closer to the main links during their feeding movements through the machine.

10. The structure defined in claim 5 in which certain of said belt-guiding wheels are provided with radially-projecting wedge-shaped flanges operative between the main and supplemental belt sections to laterally shift the latter in the manner stated.

11. In a machine of the kind described, a feed table provided with a converging belt guideway, an upper supporting frame overlying said table and provided with a converging belt guideway, a lower feed belt working in the belt guideway of said table, means supported from said table for guiding and driving said lower feed belt, an upper feed belt working in the belt guideway of said upper frame, means on said upper frame for driving and guiding said upper belt, and which belts are made up of main links and laterally movable supplemental sections, the latter of which in the movement through the respective converging guideways are moved closer and closer to said main link belt sections by lateral pressure exerted thereon by the converging guideways, and means for spreading the supplemental links after they leave the converging guideways.

12. In a feed mechanism of the kind described, cooperating upper and lower endless link belts each comprising pivotally connected main links and supplemental links, the latter being arranged one on each side of each main link and mounted for lateral sliding movements in respect thereto, said upper and lower feed belts being so arranged that the main links and left-hand supplemental links and right-hand supplemental links of the upper belt will be respectively cooperatively aligned with the main links and left-hand supplemental links and right-hand supplemental links of the lower belt, guideways for the opposing portions of the upper and lower belts, said guideways having sides that converge from the input toward the output end of the mechanism, whereby to force the supplemental link sections gradually and progressively closer to their respective main links during their operative feeding movements through the guideways, and means for spreading the supplemental links of the upper and lower belts during their inoperative movements.

OSCAR S. BOLLING.
